UNITED STATES PATENT OFFICE.

ALOYSIUS S. HAGEMAN, OF DAYTON, OHIO, ASSIGNOR TO THE ASH CABINET & MANUFACTURING COMPANY, OF DAYTON, OHIO, A CORPORATION OF OHIO.

FOLDING CHAIR.

Application filed October 15, 1927. Serial No. 226,277.

The present invention relates to chairs and particularly folding chairs. One of the objects of the present invention is to provide an improvement in chairs of the folding type which chairs can be folded or unfolded quickly and which when folded are compact and can be readily stacked on one another.

Another object is to improve the construction of folding chairs, to provide a rigid chair, and to facilitate the manufacture and thus reduce the cost thereof.

Further objects and advantages of the present invention will be apparent from the following description, reference being had to the accompanying drawing, wherein a preferred form of the present invention is clearly shown.

In the drawings:

- 20 Fig. 1 is a side view of my improved chair;
- Fig. 2 is a front view of the chair;
- Fig. 3 is a side view showing the chair partly folded;
- Fig. 4 is a side view showing same completely folded;
- 25 Fig. 5 is a fragmentary perspective view of a portion of the chair;
- Fig. 6 is a sectional view taken of line 6—6 of Fig. 1;
- Fig. 7 is a fragmentary rear view of a portion of the chair, and
- 30 Fig. 8 is a sectional view taken on line 8—8 of Fig. 7.

Referring to the drawings, the chair comprises a main frame 20 formed of channel-iron and constituted uprights 21 and 22 and provides an upper arcuate-shaped connecting portion 23. Uprights 21 and 22 provide front legs for the chair. A brace 25 connects the bottom ends of uprights 21 and 22 and a brace 26 is connected with the uprights which latter brace may be used as a foot rest. Another brace 27 connects the uprights substantially midway between the top and bottom of said uprights and upon which a seat 29 is adapted to rest. A slightly concaved back-rest 30, having its ends formed to the contour of the arcuate-shaped uprights, is suitably secured to said uprights.

50 A second frame 31 which is U-shaped provides uprights 32 and 33 and a bottom portion

34. The upper ends of the uprights 32 and 33 are pivotally connected, respectively, to uprights 21 and 22 and constitute the rear legs of the chair.

The seat 29 includes a U-shaped channel iron 36 and a seat portion 37. The portion 37 is formed to the contour of the base 38 of the channel iron and is inserted between the flanges 40 of said iron. If desired, a covered padding 42 may be placed on the top of the seat portion 37. The seat portion 37 terminates short of the iron 36 and a bolt 43 extends through said ends. Nuts 44 are threaded on the bolt, which nuts when tightened draw the ends of the iron 36 toward one another to hold the seat portion firmly in place. The ends of bolt 43 extend through the rear uprights 32 and 33 to provide a pivotal connection for the seat 29. Nuts 45 are threaded on the bolt 43 for holding the uprights 32 and 33 in place and these nuts are locked in position in any suitable manner, as for example, by riveting over the ends of the bolt 43.

U-shaped connecting members 47 each have one leg 48 thereof suitably secured as by welding, to the chair iron 36 on opposite sides of the seat 29. The other legs 49 are each pivotally connected with links 50. The opposite ends of links 50 are pivotally connected at 51 to the uprights 21 and 22.

When it is desirable to fold the chair, the seat 29 is moved upwardly, and due to the location of U-shaped connecting members 47 and links 50 with respect to the seat and uprights, the rear frame 31 will be pulled forwardly and when the upper part of chair seat is folded against the back rest 30, the rear frame 31 will be folding within the front frame 20. The recesses between the legs 48 and 49 of members 47 will receive the uprights 32 and the links 50 will be disposed between the uprights 32 and 21 on one side of the chair, as clearly shown in Figs. 7 and 8. It is to be understood that the link 50 on the opposite side of the chair will fold between uprights 33 and 22.

Thus it is apparent that the entire chair will telescope to provide a narrow structure when folded. The chair can also be changed

from folded to occupant-supporting position as readily as it can be folded. In order to move same to occupant-supporting position, it is necessary only to swing the seat down-
 5 wardly where it will rest upon the brace 27, and, when so moved, the rear frame 31 will be moved to the position shown in Fig. 1, the links 50 being disposed as shown, to limit the rearward movement of the rear frame 31.
 10 By virtue of this construction, a rigid chair has been provided which can be folded and unfolded quickly and when folded occupies only a small space and a plurality of these folded chairs can be stacked readily. The
 15 links 50 and the connections therefor are all disposed below the upper part of the seat and in such position that no protuberances are presented which may catch the clothing of the person occupying the chair.

20 The structure of the seat and the manner of assembling same provides a novel feature. After the seat portion is inserted between the flanges of the channel iron, it is held in place by the bolt which provides a pivotal connection between the seat and the chair frame. When the nuts 44 are drawn the substantially parallel portions of the iron 36 firmly engage the side edges of seat portion 37 while the bolt 43 lies adjacent the back edge of the
 25 portion 37 to prevent said portion from moving out of position in the event that the nuts 44 become loose.

While the form of embodiment of the invention as herein disclosed, constitutes a preferred form, it is to be understood that other forms might be adopted, all coming within the scope of the claims which follow.

What is claimed is as follows:

1. A folding chair comprising in combination, a main frame, a seat support carried thereby, a second frame pivotally attached to the main frame above said seat support, a seat pivotally carried by the second frame and adapted to rest on said seat support, and
 40 a link having one end thereof pivotally attached to a point on said seat lying intermediate the frames when the chair is in occupant-supporting position, said link having the other end thereof pivotally attached to the main frame below said seat support.

2. A folding chair comprising in combination, a main frame providing front leg means, a seat support carried thereby, a second frame pivotally attached to the main frame above the seat support and providing rear leg means, a seat pivotally carried by the second frame and adapted to rest on said seat support, and a link having one end thereof pivotally attached to a point on said seat
 45 lying intermediate the frames when the chair is in occupant-supporting position, said link having the other end thereof pivotally attached to the main frame below said seat support.

3. A folding chair comprising in combination, a main frame, a seat support carried thereby, a second frame pivotally attached to the main frame, a seat pivotally attached to the second frame and adapted to rest on said seat support, and a link pivotally attached to the main frame below the seat support and pivotally attached to the seat, the connection of the link being bent to permit the second frame to telescope within the main frame and the link to telescope between said frames.

4. A folding chair comprising in combination, a main frame, a second frame pivotally attached to the main frame, a seat pivotally attached to the second frame, and a link pivotally attached to the main frame, a connection for pivotally attaching said link to the seat, said connection extending outwardly from the seat and having a recess adapted to receive the second frame when the chair is folded.

5. A folding chair comprising in combination, a main frame, a second frame pivotally attached to the main frame, a seat pivotally attached to the second frame, and a link pivotally attached to the main frame, a connection for pivotally attaching said link to the seat, said connection being adapted to receive said second frame when the chair is folded and including a U-shaped member having one leg thereof connected with the link and the other corresponding leg connected with the seat.

6. A folding chair comprising in combination, a main frame, a second frame pivotally attached to the main frame, a seat pivotally attached to the second frame, and a link pivotally attached to the main frame, a connection for pivotally attaching said link to the seat, said connection being adapted to receive said second frame when the chair is folded and including a U-shaped member having one leg thereof pivotally connected with the link and the other corresponding leg connected with the seat.

7. A folding chair comprising in combination, a frame member, a chair leg pivoted to said frame member, a seat member pivoted to said leg, and a link, connecting elements between the link and members, one of said elements being U-shaped and adapted to receive the chair leg when the chair is folded, one of the legs of said U-shaped member being attached to one of said members and the other corresponding leg thereof being attached to said link.

8. A folding chair comprising in combination, a frame member, a chair leg pivoted to said frame member, a seat member pivoted to said leg, and a link, connecting elements between the link and members, one of said elements being U-shaped and adapted to receive the chair leg when the chair is folded, one of the legs of said U-shaped member be-

ing attached to one of said members and the other corresponding leg thereof being pivotally attached to said link.

9. A folding chair comprising in combination, a main frame, a seat support carried thereby, a second frame pivotally attached to the main frame, a seat pivotally attached to the second frame, a link, a connection between

the seat and link, and a connection between the main frame and link, one of said connections including a member bent to receive the second frame when the chair is folded. ¹⁰

In testimony whereof I hereto affix my signature.

ALOYSIUS S. HAGEMAN.
